Warren Platner, Foote's Bridge Road,
Guilford, Conn. 06340

Filed Aug. 27, 1973, Ser. No. 391,762

Term of patent 14 years

Int. Cl. D6—01

U.S. Cl. D6—38

FIG. 1 is a perspective view of my design for an adjustable lounge chair, as seen from one side;

FIG. 2 is a view of the chair as seen from the rear;

FIG. 3 is a perspective view of the chair as seen from one side, the back of the chair being lowered and the foot rest thereof being raised; and

FIG. 4 shows the chair in the same adjusted position as in FIG. 3, except that the arm rests are now raised.

I claim:

The ornamental design for an adjustable lounge chair, substantially as shown and described.
